Willard A. Arnold of Northampton Massachusetts
Letters Patent

This schedule is annexed to the said Letters Patent and making part of the
same containing a description in the words of the said Willard
A. Arnold himself of his improvement in the Cooking Stove."

To all persons to whom these presents shall come greeting. Be
it known that I Willard A. Arnold of Northampton in the County
of Hampshire, and Commonwealth of Massachusetts, an
iron plate worker, have invented a new and useful improvement in Cook-
ing Stoves, &c. which I have denominated Arnold's Yankee Cooking
Stove and that the following is a correct and full description of the
construction and operation of said Cooking Stove as invented in
proof and certified by me. The said invention improvement
or new combination of machinery consists of a cast iron Stove of any re-
quired dimensions standing on three or more legs, and having an ele-
gant or semi circular hearth with a sunk hearth, of two or more
inches in depth in the centre of it extending under the fire place.
Back of this is a elliptical hearth and over the same looks with it.
is a fire place having falling doors, in front and one in the end
of it for feeding the fire. Back of the fire place is a cast iron oven
having doors opening on each end of it, and the top of the oven
being in the form of an arch. Between the oven and the fire-
place is a plate or gender placed one inch or more in front of
the oven rising to the point where the arch of the oven is sprung
when it is made gradually to approach the oven until it
comes in contact with and rests upon the top of the oven.
On the side pieces of the Stove between the iron gender and
the oven are made three or more small perforations to admit air
for the purpose of regulating the heat of the oven. A passage for
the heat and draft of the fire, one inch or more in depth extend-
ing the whole breadth of the Stove and raised one or more inches
above the bottom of the bottom of the hearth of the fire place is made

386.

under the oven and up the back side of it, from whence it is conducted through a lip and collar into the funnel or conductor leading into the chimney. The passage on the back side of the oven being a little larger than that under it, another passage for heat and smoke is made from the top of the fire place and over the oven into the funnel or conductor aforesaid occupying the space between the top of the oven and the top plate of the stove back of the fire place. At the rear and lower corner of the stove below the lip and collar is a damper, which shuts off or admits the heat and smoke through the passage under and up the back side of the oven. The whole body of the stove back of the fire place is raised one or more inches higher than the front part. That part of the brick hearth which is in front of the folding door of the fire place is to be covered with a plate sliding in grooves on each side and by which the draft of the stove is to be regulated. The top plate or plates of the stove extend from the front of the fire place back to the lip and collar through which the smoke is conducted into the funnel or other outlet. There are two or more perforations in the top plate directly over the fire place for the admission of pots, kettles and other culinary utensils with rings and covers. Over the front part of the top of the oven another or more perforations for the same purpose with collars, rings and covers, back of which others can be constructed if needful to be connected with those in front by square channels for the free passage of heat and smoke from those in front to those in the rear. The top of the stove back of the fire place is elevated one or more inches above the top of the oven.

Should it be desirable to have more room for baking than is contained in the cast iron oven it may be had by placing two cylinders on the top of the stove, with doors occupying the whole or a part of the top of the stove.

Operation. By constructing a fire in the fire place the heat and smoke will pass off through the two passages above and under and back of the oven as before described through the lip and

collar into the funnel or other outlet thereof and by which the necessary heat will be generated for baking, boiling and all other culinary purposes, for which it may be required.

The said Willard A. Arnold claiming as his own invention and improvement in the Cooking Stove herein before described only the particular combination of parts and machinery as herein described and combined for that purpose. And the said Willard A. Arnold does further solemnly declare that he is a free and native born citizen of the United States.

I do testimony that the foregoing is a full and exact description and specification of the construction and operation of my said invention improvement and new combination of parts and machinery for a cooking Stove I have herunto set my hand at Northampton aforesaid this ninth day of April in the year of our Lord One thousand Eight hundred and thirty six.
